UNITED STATES PATENT OFFICE.

CHARLES WILLIAM THOMPSON, OF QUINCY, MASSACHUSETTS, ASSIGNOR OF ONE-HALF TO EDWIN J. TUCKER, OF MALDEN, MASSACHUSETTS.

FRUIT JAR, ETC.

1,420,892.

Specification of Letters Patent. Patented June 27, 1922.

Application filed November 27, 1920. Serial No. 426,688.

To all whom it may concern:

Be it known that I, CHARLES WILLIAM THOMPSON, a citizen of the United States, residing at Quincy, in the county of Norfolk, 5 and State of Massachusetts, have invented new and useful Improvements in Fruit Jars, Etc., of which the following is a specification.

This invention relates to a receptacle, such 10 as a fruit jar, having an upwardly facing packing-ring seat and a cap having a marginal portion formed to clamp a packing-ring against the seat, clamping pressure being exerted on the cap by toggles, which 15 include inner members hinged to anchoring means on the receptacle, and outer hooked members bearing on the cap, and adapted to exert downward pressure thereon when the toggles are rendered active.

20 The chief object of the invention is to provide improved means for operatively supporting the toggles on the jar in such manner that the toggles and the supporting means may be applied to and removed 25 from the jar as a unit.

The invention is embodied in the improvements which I will now proceed to describe and claim.

Of the accompanying drawings forming 30 a part of this specification,—

Figure 1 is a side elevation of a jar embodying the invention, the cap being removed.

Figure 2 is a vertical section of the jar 35 and cap, parts being broken away.

Figure 3 is an edge view, showing one of the toggles and portions of the supporting means removed from the jar.

Figure 4 is a plan view of the parts shown 40 by Figure 3.

Figure 5 is a section on line 5—5 of Figure 3.

Figure 6 is an enlargement of a portion of Figure 2, showing the toggle inactive.

45 Figure 7 is a view similar to Figure 6, showing the toggle active.

The same reference characters indicate the same parts in all of the figures.

The body of the jar 12 is preferably 50 tapering or tumbler shaped, and is provided with an annular upwardly facing seat 13 for a packing-ring 14. The body has an enlarged cylindrical peripheral portion 15 below the seat 13, and a downwardly facing 55 shoulder 16 below said portion. The cap 17

has a downwardly facing marginal portion, formed to bear on the packing-ring, and a groove 18 formed to engage the hooked toggle members hereinafter described.

The jar is provided with cap-confining 60 toggles including inner members 19, having terminal hinge pintle portions 20, and outer members 21 hinged at 22 to the inner members and provided with hooks 23, formed to engage the cap groove 18.

An important element of my invention resides in means employed for operatively supporting the toggles on the jar, and preferably embodied as the next described.

25 represents a band, preferably of wire, 70 loosely surrounding the jar below the shoulder 16, the function of said band being to confine a pair of hinge sockets 26 against the body of the jar. Said sockets engage the terminal pintles 20 to form hinge 75 connections between the toggles and the supporting means, and are provided with eyes 27 embracing portions of the band 25, lower lugs 28 engaging the shoulder 16 to prevent upward displacement of the hinge sockets 80

26, and upper confining lugs 29, normally engaging the seat 13, to prevent downward displacement of the hinge sockets. Each of said hinge sockets, its eye 27, and lugs 28 and 29, is preferably formed from an elongated flexible metal strip bent between its ends to form said socket and eye, the end portions of the strip being extended to form the lower lug 28 which is relatively short, and the upper lug 29 which is longer and is 90 provided with a hook 29^a at its upper end.

The arrangement as shown by the drawings, and particularly by Figures 6 and 7, is such that the toggles are adapted to be rendered active, as shown by Figure 7, and 95

thereby exert downward pressure on the cap, and inactive, as shown by Figure 6, to release the cap. When the toggles are inactive, the portions of the band 25, embraced by the eyes 27, spring outward sufficiently 100

to hold the hooks 29^a in contact with the seat 13. When the toggles are rendered active the said portions of the band and the lower lugs 28 are pressed inward, the longer lugs 29 being at the same time forced 105 outward or displaced by contact of their lower portions with the enlarged jar portion 15, so that their hooks 29^a are removed or displaced from the packing-ring seat 13, as shown by Figure 7, this displacement oc- 110

curring after the toggle members 21 are engaged with the cap, so that the supporting action of the lugs 29 is no longer required. The displacement of the lugs 29 enables the 5 packing-ring 14 to contact effectively with the seat 13.

When the toggles are again rendered inactive, the lugs 29 return to the position shown by Figure 6, the form of the hooks 10 29^a being such that they are adapted to enter the crevice between the seat 13 and the packing-ring.

It will be seen that the toggles and the described supporting means may be removed 15 as a unit from the jar, by springing the lugs 29 outward, and allowing the toggles and supporting means to drop, this being permitted by the tapering form of the jar body.

20 The inner toggle member 19 may be an elongated loop of resilient wire, including longitudinal portions and curved resilient necks connecting said portions. One of the longitudinal portions forms the terminal hinge pintle member 20, the other longitudinal portion forming the pintle 22^a of the hinge connection 22 between the inner and outer toggle members. The curved form of the necks connecting said longitudinal portions renders the member 19 resilient, so that the toggle is variable or conformable 25 to different receptacles and caps, in some of which the distance between the top of the cap and the shoulder 16 may be greater or less 30 than in others.

The pintle portion 22^a is preferably offset from the plane of the toggle member 19, as best shown by Figure 3, this arrangement permitting the said pintle portion to 35 swing inward to the full extent required when the toggle is active. The outer pintle member 21 may be either of open wire construction, as shown by Figure 4, or may be made of sheet metal. In the latter case, an 40 edge view of said member would be as shown by Figure 3.

I claim:

1. A jar having in combination, an upwardly facing packing-ring seat, a downwardly facing shoulder below said seat, a 45 cap formed to compress a packing-ring on said seat, cap-confining toggles provided

with terminal hinge pintles, and means for operatively supporting the toggles on the jar, said means including a band loosely 55 surrounding the jar below said shoulder, hinge sockets engaging the said terminal pintles, said sockets being provided with eyes embracing portions of the band, lower confining lugs engaging said shoulder to prevent upward displacement of the sockets, and upper confining lugs normally engaging 60 said seat to prevent downward displacement of the sockets, the arrangement being such that the toggles are adapted to be rendered active, and thereby exert downward pressure on the cap, and inactive to release the cap, the said upper lugs being automatically displaceable from the said seat and from a packing-ring thereon by the operation 65 of rendering the toggles active.

2. A jar embodying the combination specified by claim 1, the body of the jar being tapered below said shoulder, so that when the said upper lugs are displaced, the said 70 toggles and supporting means may be separated as a unit from the jar.

3. A jar embodying the combination specified by claim 1, each of said hinge sockets and its band-embracing eye and confining 75 lugs being formed from an elongated flexible metal strip, bent between its end portions to form said sockets and eye, its end portions being extended to form the said lower lug, which is relatively short, and the 80 said upper lug, which is longer and is adapted to be displaced outward by the portion of the jar above said shoulder when the accompanying toggle is rendered inactive.

4. In a jar having a closing cap, a cap- 90 confining toggle composed of an inner and an outer member, said inner member being formed as an elongated loop of resilient wire, including a longitudinal portion which forms a terminal hinge pintle, adapted to 95 engage a hinge socket secured to the jar, another longitudinal portion hinged to the outer toggle member, and curved resilient necks connecting said longitudinal portions, whereby the toggle is rendered variable. 100

In testimony whereof I have affixed my signature.

CHARLES WILLIAM THOMPSON.
